Inventor:
Charles C. Abbott,
by *Alexander S. Smith*,
His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC HEATER.

Application filed November 26, 1924. Serial No. 752,447.

To all whom it may concern:

Be it known that I, CHARLES C. ABBOTT, a citizen of the United States, residing at Pittsfield, in the county of Berkshire, State of Massachusetts, have invented certain new and useful Improvements in Electric Heaters, of which the following is a specification.

My invention relates to electric heaters, and has for its object the provision of an electric heater including means for disconnecting the heating units from the electrical supply source upon the occurrence of an excessive temperature.

My invention relates more particularly to electric heaters for oil wells. Such heaters are lowered into the well and are used to melt various deposits, such as paraffin, which tend to clog up the well and prevent the free flow of oil. The heaters during operation, therefore, are not accessible and it is impossible to observe the conditions under which they operate. There is no way of ascertaining whether the heater is operating at an excessive temperature and this might often occur with resultant damage to the heater.

In carrying out my invention I incorporate suitable protective means in the heater whereby it is automatically disconnected from the electric supply circuit upon the occurrence of a temperature which may damage it.

For a more complete understanding of my invention, reference should be had to the accompanying drawing, in which Fig. 1 is an elevation view in section of an electric heater embodying my invention; Fig. 2 is an enlarged sectional view looking upward along the line 2—2 of Fig. 1; while Fig. 3 is an enlarged elevation view in section showing details of the temperature protective device.

Referring to the drawing, in one form of my invention I utilize electric heating units of the helical coil sheathed wire type such as described and claimed in my Patent No. 1,367,341, dated February 1, 1921. The heating means consists of a plurality of lengths 10 of this helical coil sheathed wire unit, seven being shown. These lengths are spaced in parallel relation around the circumference of a circle as shown in Fig. 2. It will be understood that each of these units consists of an outer metallic sheath 11 in which is a helically shaped resistance conductor 12 embedded in compacted insulat-

ing material 13. The lower ends of the units 10 are connected to a lower head member 14, for example, by threading the ends of the sheaths as indicated at 15 and screwing them into tapped holes in the member 14. Immediately above the member 14, the units are bent inwardly together slightly so as to rest against the metallic pipe 16 and extend longitudinally thereof. Clamping members 17 are provided at intervals along the length of the heating units 10 whereby the units are secured tightly against pipe 16 in good heat conducting relation therewith. The pipe 16 is somewhat longer than the units 10 and has its upper end threaded at 18 and screwed tightly in a tapped hole in an upper head member 19. The member 19 is provided with a bore 20 in which the ends of the units extend and are held tightly clamped in proper spaced relation against the pipe 16 by means of radially extending set screws 21 in member 19. As shown in Fig. 2 the set screws 21 are spaced at intervals around the periphery of member 19 and are screwed tightly between each pair of units, the screws being of greater diameter than the space between the units so that the units are thereby clamped securely in place.

The heating units 10 have their metallic sheaths sealed over at their upper ends so as to tightly close them and prevent the entrance of moisture, etc. The resistance conductor 12 in each unit is electrically connected to the sheath at the upper end and is therefore grounded to the member 19 and other metallic parts of the heater. At their lower ends the resistance conductors are brought out and connected to suitable terminals 22 which may be insulated from the sheaths of the units by insulating washers 23. The terminals 22 of the units are electrically connected by means of members 24 to a common connector ring 25 which is in turn electrically connected through flexible conductor strip 26 to the lower end of a conductor rod 27 extending upward centrally of the pipe 16. At intervals along the length of the rod 27 are suitable fusible devices 28 which are arranged to break the electric circuit for the heating units upon the occurrence of an excessive temperature. The upper end of rod 27 is electrically secured to a terminal 29 which extends centrally through the bottom of metallic receptacle member 30 and is secured to the mem-

ber 30 in insulated relation therewith. Preferably the terminal 29 is inserted in an insulating bushing 31 which is secured in a metallic bushing 32 having its upper end provided with a flange 33 and its lower end threaded so that it may be secured to the member 30 by means of a suitable nut 34. A coupling 35 may be provided for connecting rod 27 to the lower end of the terminal 10 29. The receptacle member 30 has its lower end threaded at 36 and screwed tightly in a tapped bore 37 in the upper end of member 19.

15 A helical spring 38 is provided on the lower end of rod 27 and seated on the terminal ring 25. When the rod 27 has been secured in place to the terminal 29 this spring is under compression so that when any one or more of fuses 28 melts the lower 20 portion of rod 27 will be forced quickly downward by spring 38 so as to assure a quick and effective opening of an electric heating circuit. The heater is sealed at its lower end by means of a metallic cap member 40, the upper end of which is threaded at 41 and secured tightly in the tapped bore of member 14. In order to permit the lower end of rod 27 to be forced downward for an appreciable distance and thus assure the 30 opening of the heating circuit, the member 40 is elongated and provided with an elongated bore 41' to receive the end of rod 27. Preferably a cylindrical insulator 42 is provided in the bore 41' for insulating the conducting strip 26 from the member 40. Insulating tubes 43 are provided at intervals on the rod 27 to prevent its coming in contact with pipe 16.

As shown in Fig. 3, each of the fuses 28 40 may comprise an outer tubular member 45 made of aluminum. This member 45 is tapped at each end a considerable distance and has inserted in it a short rod 46 made of zinc. This rod 46 may be secured in 45 place by means of screws 47 and 48 inserted in the ends of member 45. The screws are seated tightly against the ends of the zinc bar 46 and secure it rigidly as well as forming a good electrical connection. These 50 fuses 28 are inserted by threading the ends of the various sections of the rod 27 and screwing them tightly in the fuses which form mechanical and electrical connections between the sections. Peripheral grooves 49 55 and 50 are provided in the member 45 near the respective ends of rod 46. The object of the grooves is to reduce the cross section of the member 45 at these points and thus assure that rupture of member 45 upon the 60 occurrence of an excessive temperature will occur at some point along the length of the zinc rod 46.

The purpose of the zinc rod is to smother the arc formed by rupture of the heating 65 circuit. It will be understood that the kilo-

watt capacity of heaters of this type is fairly large and consequently there is a correspondingly large current to be ruptured. The zinc melts at a lower temperature than the aluminum and will be in a molten condition when the member 45 has been weakened to such an extent that spring 38 will break it. The oxide fumes of the zinc quickly smother the arc. A plurality of fuses are used to provide against local overheating at 70 some point along the length of the heater. The fuses operate to open the circuit at a temperature somewhat less than the maximum safe operating temperature of the heating units. 75

80 A metallic cap 51 is preferably screwed on the tapped upper end of member 30. A central bore 52 is provided in the cap 51 through which a suitable electrical cable 53 extends. This cable is preferably armored and forms the support for the heater by means of which the heater is lowered into the well. It is also provided with a central insulated electrical conductor for supplying the heating units. The return electrical circuit for the heating units is through the armor of the cable. 85

90 In order to form a mechanical and also electrical connection between the armor of the cable 53 and the outer metal parts of the heater, the wires 54 forming the armor of the cable are secured between a central ring member 55 and two outer ring members 56 and 57. For example, the outermost layer of wires are bent outward between the rings 55 and 56 while the next layer of wires are bent outward between the rings 55 and 57. The rings are then clamped tightly together by means of bolts 58. As an additional means of securing the ends of the wires the 95 central ring 55 may be provided with a peripheral groove in which the projecting ends of the wires may be laid and then secured by means of a plurality of turns of wire 59 wrapped over them. The extreme ends of the wires may then be bent back over the turns 59 as indicated at 60 and 61. A head is thus formed on the end of the cable 53 by the rings 55, 56 and 57 secured to its armor. After the rings have been secured to the armor, the cap 51, which may previously have been slipped on the cable, is slipped down over the rings and screwed on the member 30, the cable and member 30 being held from twisting. The cap 51 is 100 screwed down tightly on the head formed by the rings, whereby the head is clamped between the cap and the upper end of member 30. 105

110 The central insulated conductor 62 of the cable is connected to the terminal 29. A circuit is thus completed leading through rod 27, the flexible strip 26, and washer 25 to the resistor conductors in the various units, 115 and then through the resistance conductors 120 125

to the outer metallic parts of the heater, the return circuit being completed through the armor 53 of the cable.

The heater is thoroughly sealed at the upper end by means of a suitable insulating material 63, such as an asphaltic compound, which is poured in a molten condition into the member 30, for example, through apertures in the sides which are then closed by plugs 64. To prevent seepage of oil therethrough the metals used in the construction of the heater should be close grained. Preferably, steel is used. All threaded joints are provided with tapered threads so as to be oil-tight.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States is:

1. An electric heater comprising a tubular member, a plurality of electric heating units grouped around said member in good heat conducting relation therewith, a conducting rod extending through said tubular member forming a part of a heating circuit for said units, and a fusible cut-out in said conducting rod.

2. An electric heater comprising a metallic tubular member, a plurality of electric heating units secured around said member in good heat conducting relation therewith, a conducting rod extending through said tubular member forming a part of the electric circuit for said units, a fusible cut-out in said conducting rod, and means for applying a tension to said rod whereby said cut-out is ruptured to open the heating circuit upon the occurrence of a predetermined temperature.

3. An electric heater comprising a metallic tubular member, a plurality of electric heating units secured around said member in good heat conducting relation therewith, a conducting rod extending through said tubular member forming a part of the electric circuit for said units, a fusible cut-out in said conducting rod, head members secured to and closing the ends of said tubular member, an electrical conductor mechanically secured to one of said head members whereby the heater may be lifted, and an electrical connection between said conductor and said rod.

4. An electric heater comprising a tubular member, upper and lower heads secured to and closing the ends of said tubular member, elongated heating units arranged

longitudinally of said tubular member and secured in good heat conducting relation therewith, the lower ends of said units extending through said lower head member, a conducting rod extending centrally of said tubular member, a fusible cut-out in said rod, electrical connections between the lower end of said rod and said heating units, and means for applying a tension to said rod.

5. An electric heater comprising a pair of head members, a tubular member connecting said head members, a plurality of heating units secured around said tubular member in good heat conducting heat relation therewith, a common electrical connection for said heating units in one of said head members, a conducting rod extending through said tubular member, an electrical connection between one end of said rod and said common connection, fusible cut-outs spaced at intervals along said rod, and means for applying a tension to said rod whereby the electric heating circuit is opened therethrough upon the occurrence of a predetermined temperature.

6. An electric heater arranged to be lowered into an oil well comprising upper and lower hollow heads, a tubular member connecting said heads, a plurality of elongated heating units secured around said tubular member in good heat conducting relation therewith, the lower ends of said units extending into said lower head member, a common electrical connection for said heating units in said lower head member, a conducting rod electrically connected to said common connection and extending upward centrally of said tubular member, an electrical conductor mechanically secured to said upper head and electrically connected to said rod, means for applying tension to said rod, and fusible cut-outs spaced at intervals in said rod.

7. The combination with an electric heater, of a metallic member included in the circuit of said heater adapted to fuse and open the circuit of said heater upon the occurrence of a predetermined temperature, and a second metallic member having a lower melting point enclosed by the first arranged to fuse and extinguish the electric arc formed when the circuit of said heater is opened by rupture of said first member.

8. The combination with an electric heater, of an outer member made of aluminum included in the circuit of said heater, and an inner member made of zinc inside said outer member arranged to fuse before said outer member and extinguish the electric arc formed when the circuit of said heater is opened by rupture of said outer member upon the occurrence of a predetermined temperature.

9. The combination with an electric heater, of an outer tubular member included in the

circuit of said heater, and a rod of a metal having a lower melting point inside said tubular member arranged to fuse and extinguish the electric arc formed when the 5 circuit of said heater is opened by rupture of said outer member upon the occurrence of a predetermined temperature.

10. The combination with an electric heater, of a conducting rod included in the 10 electric circuit of said heater divided into sections, a tubular member made of aluminum forming a mechanical connection be-

tween said sections and normally closing the circuit of said heater through said sections, means for applying a tension to said rod, and a zinc rod inside said tubular member arranged to fuse and extinguish the arc formed when the circuit of said heater is opened by rupture of said tubular member upon the occurrence of a predetermined temperature. 20

In witness whereof, I have hereunto set my hand this 20th day of November 1924.

CHARLES C. ABBOTT.
